United States Patent Office.

JOHN M. HALL, OF PHILADELPHIA, PENNSYLVANIA.

Design No. 3,063, dated June 2, 1868.

DESIGN FOR A BURIAL-CASKET.

The Schedule referred to in these Letters Patent and making part of the same.

TO ALL WHOM IT MAY CONCERN:

Be it known that I, JOHN M. HALL, of the city and county of Philadelphia, and State of Pennsylvania, have invented a new and useful Design for Burial-Caskets; and I do hereby declare the following to be a description of the same, reference being had to the accompanying drawings, making part of this specification, in which—

Figure 1 is a top or plan view of the design illustrating my invention.

Figure 2 is a side view thereof.

Figure 3 is a vertical section in line $z z$, fig. 2.

Similar letters of reference indicate corresponding parts in the several figures.

My invention consists in the peculiar configuration of a casket or coffin, whereby a neat and attractive design is produced, as is illustrated in the drawings.

A represents the casket or coffin. Its sides, $a a$, run parallel to each other to the point b , where each end turns inward and forms four outwardly-rounded corners, $c c$.

The rounded ends are joined to the head and foot-pieces $d d$, so that each side runs in an unbroken line from end to end, as shown in figs. 1 and 2.

The lid B will conform with the body A, and be somewhat raised on top, and have a single moulding, e. The under side of the lid will present the appearance of a truncated pyramid.

Having thus described my invention, what I claim as new, and desire to secure by Letters Patent, is—

The design for the configuration of the burial-casket, substantially as represented and described.

To the above I have signed my name, this 11th day of April, 1868.

JOHN M. HALL.
